UNITED STATES PATENT OFFICE.

WILLIAM DAVIS, OF PHILADELPHIA, PENNSYLVANIA, ASSIGNOR TO THE WILLIAM D. DAVIS MACHINE COMPANY, OF PHILADELPHIA, PENNSYLVANIA, A CORPORATION OF PENNSYLVANIA.

AUTOMATIC MAIL-BAG CATCHER AND DELIVERER.

Application filed June 18, 1920. Serial No. 390,052.

To all whom it may concern:

Be it known that I, WILLIAM DAVIS, a citizen of the United States, residing at Philadelphia, in the county of Philadelphia and State of Pennsylvania, have invented 5 certain new and useful Improvements in Automatic Mail-Bag Catchers and Deliverers, of which the following is a specification.

10 This invention relates to improvements in mail bag catching and delivering mechanisms for use on railway cars and adapted to automatically catch or deliver or simultaneously catch and deliver the mail bag or bags.

One of the primary objects of the present invention is to provide a mechanism so constructed as to occupy a minimum space and lie wholly within the door opening of the car 20 when in inactive position and which may be set for operation wholly from within the car and without the necessity of the mail clerk projecting his arms or body beyond the door opening of the car. Incidentally 25 the invention contemplates so constructing the mechanism that the same may be returned to inactive position after the transfer of the mail bag or bags has been effected, without the necessity of the mail clerk exposing his body or limbs to danger.

Another object of the invention is to so construct the mechanism that it will operate to automatically catch and deliver the bags simultaneously and consequently at the same 35 point, so that a bag to be delivered is deposited at a station substantially at the same point at which the other bag is caught by the mechanism, thus economizing in space at the station platform and minimizing the labor 40 imposed upon the station agent in removing the delivered bag and in placing the bag to be caught.

Another object of the invention is to so construct the mechanism as to provide for instant release of the bag to be delivered at 45 the moment the mechanism operates for this purpose so that no injury can result to the bag through being temporarily retained by the mechanism in a partially suspended condition.

Another object of the invention is to provide for the instant and positive release of the bag to be delivered from the mechanism both under conditions where a bag is to be

caught and where a bag is not to be caught, 55 the mechanism being likewise adapted to operate equally as effectively under reverse conditions or in other words as regards the catching or taking on of a bag.

Another object of the invention is to so 60 construct the mechanism that it will operate to positively engage and securely hold or retain the bag caught thereby.

In the accompanying drawings:

Figure 1 is a plan view of the mechanism 65 embodying the invention in active position and mounted within the doorway of a railway mail car;

Figure 2 is a similar view illustrating the 70 positions assumed by the parts when the mechanism is tripped in catching or delivering a bag;

Figure 3 is a transverse sectional view 75 taken substantially on the line 3—3 of Figure 1 looking in the direction indicated by the arrows;

Figure 4 is a detail sectional view taken 80 substantially on the line 4—4 of Figure 1;

Figure 5 is a similar view on the line 5—5 85 of Figure 1;

Figure 6 is a similar view on the line 6—6 90 of Figure 1; and

Figure 7 is a similar view on the line 7—7 95 of Figure 1.

In the drawings the numeral 1 indicates 85 the door opening of a railway mail car at the opposite sides of which opening are mounted bearings 2 as clearly shown in Figures 1 and 2 of the drawings. The mechanism embodying the invention comprises a supporting frame structure which is indicated in general by the numeral 3 and which comprises an arcuate body portion 4 somewhat more than a semi-circle in extent and providing a mail bag receiving recess 5 having a 90 throat 6. The frame body 4 is formed at opposite sides of the throat 6 with laterally aligned extensions 7 and 8 provided respectively with trunnions 9 and 10 which rotatably fit within the bearings 2 so that the frame structure may be swung to assume a vertical position within the door opening or a horizontal position as illustrated in Figures 1 and 2. In order to provide for ready swinging of the frame structure to 100 either of the positions stated, a handle 11 is provided upon the body 4 at the closed side of the body and in position where it may be

conveniently grasped by the mail clerk within the car. In order that the structure may be maintained in either position to which it is adjusted, a rack wheel 12 is fixed upon 5 one of the trunnions as for example the trunnion 9, and a pawl 13 is mounted upon the door frame or upon the adjacent bearing 2 and coacts with the said rack wheel for the purpose stated. At that side at which the 10 extension 7 is located, the body 4 is provided with a catching arm 14 which extends diagonally outwardly from and across the throat 6 and consequently at an angle to and opposite the extension 8, this arm being rigid 15 with relation to the body 4 and being adapted to initially engage the bag to be caught and which bag is illustrated in a general way in Figure 1 and indicated by the reference letter A.

20 At this point it will be evident that when the frame structure 3 is adjusted to assume a horizontal position as shown for example in Figure 1, the arm 14 will project beyond the door opening of the car in position to engage the bag A which is supported in any suitable manner beside the track at the station, and in order that the bag, when it enters the recess or pocket 5, may be securely retained therein, a bag retaining means is 25 provided and is arranged to be automatically actuated at the time the bag is engaged. This means is indicated in general by the numeral 15, and the same comprises a pair of arcuate bag embracing members 16 30 having substantially the same curvature and extent as the body 4 of the said frame structure and arranged one above and the other below said body. A pivot bolt 17 is passed through these members 16 and through the said body 4 and serves to support the said members in the positions stated so that they may swing in unison across the recess or pocket 5. The members are designed to be 35 automatically tripped and swung in the manner stated so as to partly embrace a mail bag delivered into the pocket 5, and in order that the members may be restored to their normal position, an operating handle 18 is preferably provided upon the upper one of the 40 said members 16 in position to be located within the car and within convenient reach of the mail clerk attending the operation of the mechanism. At that side of the throat 6 of the frame structure 3 at which the extension 7 is located, a pin or bolt 19 is secured through the members 16 and operates in a slot 20 formed in the member 4 concentric to the pivot 17. Also at this side of the structure, the members 16 are provided 45 with extensions or arms 21 which in the normal positions of the parts extend longitudinally above and below the inner portion of the arm 14. Substantially opposite the inner end of the extension 7, the body 4 is 50 formed with a seat 22, and the members 16

at the opposite side of the structure are provided with heads 23 designed to be moved toward and substantially engage within the seat 22 when the retaining means 15 is swung about its pivot 17 to the position shown in 55 Figure 2. Also at this side of the means 15, the embracing members 16 are formed with extensions or arms 24 which are preferably of the arcuate form illustrated in Figures 1 and 2 and which extend laterally and outwardly above and below the extension 8 with their extremities terminating beyond the forward side of said extension where they are connected by a bolt 25. In order to guard and brace the arms 24, the extension 8 is provided with an arcuate guiding portion 26 which extends between the arms 24, and it is preferable that the convex sides of these arms be provided with teeth 27 at suitable intervals to provide for the breaking off of ice 60 which might accumulate upon the extension 8 and its guiding portion 26.

In order that the movement of the members 16 may be cushioned, buffer means is provided and comprises a socket 28 formed or provided upon the upper side of the extension 7 of the said member 3, and a plunger comprising a head 29 and stem 30 has its said stem slidably fitted into the said socket, a pin or stud 31 being provided upon the stem 35 and working in a slot 32 in the socket so as to limit the outward movement of the plunger. The plunger is cushioned by a spring 33 upon the stem of the plunger bearing between the end of the socket 28 and the head 29. A buffer element 34 is mounted in any suitable manner at the inner end of the arm 21 and is designed to strike against the plunger head 29 when the members 16 have been swung to the limit of their movement in 70 the direction to retain the caught bag.

In order that the bag retaining means 15 may be actuated automatically when the bag to be caught is engaged by the arm 14, a tripping member, indicated in general by the 75 numeral 35 is provided and comprises a pair of arcuate trip arms 36 arranged one above and the other below the said arm 14, the arms 36 being pivotally mounted as at 37 and having operative connection as at 38 with the arms 21. The arms 36 are so arranged that normally they will extend at their convex sides part way across the space between the arm 14 and the member 26 of the extension 8. Therefore the said convex sides of the arms 36 are in the path of movement of the bag A as the bag enters between the arm 14 and extension 8 and passes to the throat 6, and as the bag rides past the said arms 36 the arms will be swung upon their pivot 37 to act 85 upon the arms 21 through the connections 38 and effect swinging movement of the members 16 to position to partly embrace the bag A which has by this time become lodged within the recess 5.

To provide for the delivery of a mail bag, the mechanism embodies means for supporting such a bag and for automatically releasing the same at the time such delivery is to be effected, and the component parts of this means are supported upon a frame extension which is indicated in general by the numeral 39 and which is carried upon the outer side of the arm 14 and may be cast integral therewith or otherwise arranged. This frame extension includes a member 40 constituting a mounting for the arms 36 and their pivot 37, and it further includes arms 41 which are provided at their outer ends with laterally directed fingers 42 to which may be fitted suspension rings 43 upon the bag to be delivered and which bag is indicated by the reference letter B. The numeral 44 indicates a sleeve bearing which is arranged within the frame extension 39, and slidably fitted in the bore of this bearing is a stem 45 upon the rear side of a shiftable member 46 in turn supported for sliding movement upon the arms 41 of the said frame extension. The member 46 constitutes an ejector and is provided with fingers 47 which project into engagement with the fingers 42 and are provided with shoulders 48 movable along the said fingers 42 longitudinally thereof in the sliding or shifting movement of the member 46. Other fingers 49 project from the member 46 with their extremities in close proximity to or contact with the fingers 42, and these fingers 49 are spaced from the respective shoulders 48 a distance sufficient to accommodate the rings 43. It will now be evident that when the member 46 has been shifted to the right in Figure 1 of the drawings until the faces of the shoulders 48 substantially register with the extremities of the fingers 42, the rings 43 of the bag to be supported may be placed in position and engaged over the ends of the said fingers 42, and the member 46 then slid toward the left in said figure whereby to confine the rings 43 between the said shoulders 48 and fingers 49 as shown in Figure 1. With the parts in this position the rings 43 which suspend the bag B will be held against accidental disengagement from the fingers 42 and the bag will be securely suspended. However upon shifting of the member 46 toward the right in said Figure 1, the rings will be immediately disengaged from the fingers thus permitting the bag to drop. In order that such movement of the member 46 may take place simultaneously with engagement of the bag A with the arms 36, the arms at their inner ends are provided with extensions 50 projecting above and below the adjacent end of the member 46 and slotted to receive a pin 52 fitted through said extensions 50. It will now be evident that when the arms 36 are engaged by the bag A and

are swung upon their pivot 37, the member 46 will be pulled or shifted in a direction to disengage the rings 43 of the bag B from the suspending fingers 42.

At times it may be required to discharge a bag from the mechanism at a station without catching another bag and in order that this may be effected automatically, a spindle 53 is mounted in a suitable bearing 54 upon the member 40 of the frame extension 39 and is provided with a depending cranked trip arm 55 designed, when in downwardly swung position, to be engageable with any suitable trip device arranged at the point of delivery of the mail bag. A pinion 56 is fixed upon the spindle 53, and a dog 57 rests in engagement with the said pinion and is pivotally mounted as at 58 upon one end of a bracket rod 59 mounted upon the member 46. It will now be apparent that when the cranked trip arm 55 is struck and actuated, a pull will be exerted upon the member 46 through the medium of the pinion 56 and the dog 57.

Having thus described the invention what is claimed as new is:

1. In mail bag catching and delivering mechanism, a frame comprising a bag-receiving portion and a guiding portion to direct a bag into the receiving portion, bag-embracing means supported by the frame and movable with relation thereto to embrace a bag within the receiving portion of the frame, means for supporting a bag to be delivered, means for ejecting a bag from said supporting means, and trip means common to the bag-embracing means and said ejecting means to simultaneously operate the same.

2. In mail bag catching and delivering mechanism, a bag receiving frame, bag embracing means supported thereby and movable with relation thereto to embrace a bag received within the frame, bag delivery means, and trip means common to the bag embracing means and the bag delivery means to simultaneously operate the same, the said trip means comprising a pivotally mounted arm operatively connected with the embracing means and delivery means and having a bowed side presented in the path of a bag to be caught.

3. In mail bag catching and delivering mechanism, a bag receiving frame having a bag receiving recess and a throat leading thereto, bag embracing means supported by the frame and movable across the throat to embrace a bag received within the recess, and bag tripped means operable to automatically actuate the embracing means and comprising an arcuate arm having its convex side positioned to be engaged by the bag to be caught, the said arm being pivotally supported in outwardly spaced relation to the bag-receiving recess and throat and

operatively connected with the said embracing means.

4. In mail bag catching and delivering mechanism, a bag receiving frame having a bag receiving recess and a throat leading thereto, bag embracing means supported upon the frame and movable across the throat to embrace a bag received within the recess, the throat being normally unobstructed bag delivery means, and trip means common to the bag embracing means and delivery means to simultaneously operate the same.

5. In mail bag catching and delivering mechanism, bag receiving means embodying a member movable to embrace a bag to be caught, means for supporting a bag to be delivered, a shiftable member for discharging the bag from said supporting means, and trip means operable by the caught bag to actuate the embracing means and the said shiftable member.

6. In mail bag catching and delivering mechanism, bag receiving means embodying a member movable to embrace a bag to be caught, means for supporting a bag to be delivered, a shiftable member for discharging the bag from said supporting means, trip means operable by the caught bag to actuate the embracing means and the said shiftable member, and means operable by abutment independently of the said trip means for shifting the said shiftable member.

35. 7. In mail bag catching and delivering mechanism, a bag receiving frame, a bag embracing member pivotally supported upon the bag receiving frame and movable to position to embrace a bag received within the frame, a relatively rigid bag supporting finger, an ejecting member shiftable with relation thereto to displace from the finger a bag attached element engaged therewith, and an abutment arm pivotally mounted upon the bag receiving frame and having a portion normally projecting in the path of

a bag entering said frame, the said arm having operative connection with the shiftable member and with the bag embracing member.

8. In mail bag catching and delivering mechanism, a bag receiving frame, a bag embracing member pivotally supported upon the bag receiving frame and movable to position to embrace a bag received within the frame, a relatively rigid bag supporting finger, an ejecting member shiftable with relation thereto to displace from the finger a bag attached element engaged therewith, an abutment arm pivotally mounted upon the bag receiving frame and having a portion normally projecting in the path of a bag entering said frame, the said arm having operative connection with the shiftable member and with the bag embracing member, an oscillatory abutment arm mounted upon the bag receiving frame, and operative connection between the last-mentioned arm and the shiftable member for effecting operation of the shiftable member independently of the first-mentioned abutment arm when the last-mentioned arm engages a fixed abutment.

9. In mail bag catching and delivering mechanism, a frame having a throat extending thereacross intermediate its ends and a bag-receiving recess at one side of and communicating with the throat, a bag-embracing member mounted on the frame around the bag-receiving recess therein and movable upon the frame to extend across the throat and embrace a bag directed into the recess, and a trip mounted on the frame at the opposite side of the throat from the bag-embracing member in position to be engaged by a bag to be caught and operatively connected with the bag-embracing member whereby said member will be caused to embrace the bag.

WILLIAM DAVIS.
